DESIGN FOR A BATHING CAP

William C. Pentz, North Canton, Ohio, assignor
to The B. F. Goodrich Company, New York, N. Y., a corporation of New York

Application February 20, 1934, Serial No. 50,782

Term of patent 3½ years

To all whom it may concern:

Be it known that I, WILLIAM C. PENTZ, a citizen of the United States, residing at North Canton, in the county of Stark and State of Ohio, have invented a new, original, and ornamental Design for a Bathing Cap, of which the following is a specification, reference being had to the accompanying drawing, forming a part thereof.

The accompanying drawing shows a side elevation of a bathing cap embodying my design.

I claim:

The ornamental design for a bathing cap as shown.

WILLIAM C. PENTZ.
